UNITED STATES PATENT OFFICE.

HARRY W. LOWE, OF INDIANAPOLIS, INDIANA, ASSIGNOR, BY MESNE ASSIGNMENTS, TO INDIANA CANNING MACHINERY CO., OF INDIANAPOLIS, INDIANA, A CORPORATION OF INDIANA.

PULPING-MACHINE.

1,366,011.

Specification of Letters Patent. Patented Jan. 18, 1921.

Application filed December 31, 1918. Serial No. 269,146.

To all whom it may concern:

Be it known that I, HARRY W. LOWE, a citizen of the United States, residing at Indianapolis, in the county of Marion and 5 State of Indiana, have invented a new and useful Pulping-Machine, of which the following is a specification.

It is the object of my invention to provide a pulping machine construction which can 10 be easily opened so as to give access to all the internal parts and thus facilitate cleaning and promote the maintenance of sanitary conditions, which when in operation is effective to produce pulping throughout its 15 entire circumference, and from which the discharge of the refuse after pulping is obtained peripherally by centrifugal force so as to minimize the danger of clogging and provide an easier control of the discharge. 20 In carrying out these objects, I provide a pulping machine in which the pulping screen is made of two separate parts having hinge 25 mountings so that they may be opened to give access to the inside of the screen and to the working parts within the screen; and I provide a pulping screen above as well as 30 below the horizontal plane through the axis of the structure, so that the juices and pulp may be forced through the screen throughout its circumference; and I provide at the 35 discharge end of the structure one or more peripheral openings the size of which is suitably controlled, from which openings the refuse after the pulping operation is discharged by the action of centrifugal force.

The accompanying drawing illustrates my invention.

Figure 1 is a perspective view of a pulping machine embodying my invention, with the 40 cover removed and the two-part screen opened; Fig. 2 is a transverse vertical section through the refuse-discharge head, taken substantially on the line 2—2 of Fig. 3; Fig. 3 is a partial section taken on the line 3—3 45 of Fig. 2; and Fig. 4 is a transverse section through the pulping machine, showing the two-part screen closed and the removable cover in place, but omitting the frame and the drain pan.

50 A supporting frame 10 supports the two end members 11 and 12 in any suitable manner, and also has bearings 13 for a shaft 14, which is provided with suitable arms 15 carrying the paddles 16. The intake end

member is annular, to permit the supplying 55 through its central opening 17 of the fruit or vegetables to be pulped; and is provided with any suitable hopper construction 18 leading to such central opening. The shaft 14 extends through the two end members, 60 and is provided with any suitable driving device (not shown).

Two suitably supported hinge rods 20 extend side by side lengthwise of the structure, preferably below the shaft 14; and on these 65 two hinge rods are pivotally mounted the carrying frames 21 of two semi-cylindrical screens 22. The frames are provided with any suitable latching devices 23 for holding their upper edges together when desired, so 70 that the two semi-cylindrical screens will together form a complete cylindrical screen inclosing the shaft 14 and paddles 16 and close to the inside surface of which the paddles 16 travel when the shaft 14 is rotated. 75 By releasing the latches 23, the two semi-cylindrical screens may be swung apart about their hinge mountings on the hinge rods 20, as illustrated in Fig. 1, so as to give ready access to the inside surface of the 80 screen and to the parts inclosed by the screen. The two end members are provided with annular shoulders 24, upon which the curved end edges of the screen-carrying frames 21 bear when the screen is closed as shown in 85 Fig. 4, so as to provide substantially tight joints between such screen-carrying frames and the end members.

The end member 12 at the discharge end of the machine is provided with one or more 90 peripheral discharge openings 25, located between the end wall 26 of such end member and an intermediate outwardly projecting flange 27 from which the annular flange which provides the shoulder 24 projects. 95 These peripheral discharge openings 25 are conveniently located substantially opposite each other, in about the horizontal plane of the shaft 14, and are provided with adjustable curved gate valves 28 by which the sizes 100 of such openings may be adjusted and either opening may be completely closed. The openings 25 preferably are continued through outwardly projecting chutes, of which part of the walls are formed by continuations of the end wall 26 and flange 27. 105

Below the screen cylinder and its supporting hinge rods 20 and supported in any suit-

able manner is a drain pan 30, which is provided with any suitable discharge outlet 31 for discharging the pulp and juice which are caught in the drain pan. This drain pan preferably extends up to the horizontal members 32 of the frame 10, which horizontal members inclose an opening through which the pulp and juice drip into the drain pan 30. These horizontal members 32 also support a removable cover 33, which retains the pulp and juice thrown out through the screen 22 and guide such pulp and juice downward to the drain pan.

In operation, the two semi-cylindrical screen parts are closed to form a complete cylindrical screen, and the cover 33 is in place, as illustrated in Fig. 4. The material to be pulped, such as vegetables or fruit, is supplied to the interior of the screen 22, through any suitable devices or mechanism, which may be simply the feed hopper 18 leading to the feed-opening 17. After this material reaches the inside of the cylindrical screen, the shaft 14 being in operation, such material is agitated by the moving paddles 16 and thrown outward thereby against the inside surface of the cylindrical screen 22 to cause juice and pulp from such material to be forced out through the screen. The paddles 16 travel sufficiently close to the inside surface of this screen so that they also positively force pulp and juice from the material outward through the screen. The pulp and juice are thus forced out through the screen throughout the circumference thereof, and are caught by the cover 33 and directed downwardly thereby through the opening in the rectangular frame members 32 into the drain pan 30, whence the juice and pulp are drawn off through the discharge opening 31. The refuse which is not forced out through the screen 22 works down toward the end member 12 at the discharge end of the machine, being continuously held out against the inside periphery of the screen by the centrifugal action produced by the paddles 16. When this refuse reaches the end member 12, it is thrown by this same centrifugal force outward through the peripheral openings 25 or either of them, according to whether one or both of them are open. By adjusting the gate valves 28, the discharge of the refuse is controlled, so that such discharge is retarded to any extent necessary to produce the desired qualities in the refuse and in the pulp and juice. By closing the gates 28 to a greater extent, the discharge of the refuse is more greatly retarded so that it is maintained in the machine longer and is drier when discharged, because more of the liquid and the softer matter is forced outward through the screen and caught in the drain pan.

When the pulping operation is over, and the machine is stopped, cleaning can be

readily obtained by removing the cover 23 and opening the two semi-cylindrical screen parts, thus giving access to the inside surface of the screen and to all the working parts.

70

I claim as my invention:

1. A pulping machine, comprising a substantially horizontal shaft carrying paddles, an inclosure in which said shaft and paddles rotate, said inclosure including a screen which extends completely around the shaft and paddles, a drain pan below said inclosure, the upper edge of said drain pan being below the axis of said shaft so that access is afforded to the lower exterior of the inclosure, and a removable cover over said screen and spaced therefrom and extending down on both sides of the inclosure to a point below the axis of the shaft, the space within said cover leading to said drain pan.

2. A pulping machine, comprising a substantially horizontal shaft carrying paddles, an openable inclosure in which said shaft and paddles rotate, said inclosure including a screen which extends completely around the shaft and paddles, a drain pan below said inclosure, the upper edge of said drain pan being below the axis of said shaft so that access is afforded to the lower exterior of the inclosure, and a cover over said screen and spaced therefrom and extending down on both sides of the inclosure to a point below the axis of the shaft, the space within said cover leading to said drain pan, said cover being movable relatively to the inclosure to give access thereto.

3. A pulping machine, comprising a rotatable agitating element including a substantially horizontal shaft carrying paddles, and openable inclosure in which said shaft and paddles rotate, said inclosure including a screen which extends completely around the shaft and paddles, said screen being spaced from said rotatable element, and a drain pan below said inclosure to receive the material forced through said screen, the upper edge of said drain pan being below the axis of said shaft so that access is afforded to the lower exterior of the inclosure.

4. A pulping machine, comprising a substantially horizontal shaft carrying paddles, a laterally openable inclosure in which said shaft and paddles rotate, said inclosure including a cylindrical screen which extends completely around the shaft and paddles, and a drain pan below said inclosure, the upper edge of said drain pan being lower than the axis of said shaft so that the drain pan will not interfere with the opening of the inclosure.

5. A pulping machine, comprising a rotatable agitating element including a substantially horizontal shaft carrying paddles,

130

an inclosure in which said agitator rotates, said inclosure comprising two hinge-mounted parts which are relatively movable so that when in one position they inclose the 5 agitator and when in another position the inclosure is open to give access to the interior and to the agitator, each of said parts including an arc-shaped screen, and an inclosing housing around said inclosure for 10 catching the liquid which is pressed out through the screen.

6. A pulping machine, comprising a rotatable agitating element including a substantially horizontal shaft carrying paddles, 15 and a substantially cylindrical inclosure in which said agitator rotates, said inclosure comprising two semi-cylindrical hinge-mounted parts pivoted below said shaft so that the two parts may be swung together to 20 form a complete cylinder or may be separated to give access to their inside surfaces and to the agitator, each of said hinge-mounted parts including an arc-shaped screen through which material may be 25 forced by said agitator.

7. A pumping machine, comprising a rotatable agitating element including a substantially horizontal shaft carrying paddles, and a substantially cylindrical inclosure in 30 which said agitator rotates, said inclosure comprising two semi-cylindrical hinge-mounted screens pivoted below said shaft so that the two screens may be swung together to form a complete cylindrical screen or may be separated to give access to 35 their inside surfaces and to the agitator.

8. A pulping machine, comprising a rotatable agitating element including a substantially horizontal shaft carrying paddles, 40 and an inclosure in which said agitator rotates, said inclosure comprising two parts which are both movable relatively to the shaft axis so that when in one position they inclose the agitator and when in another 45 position the inclosure is open and both parts are separated farther than normal from the agitator to give access to the interior of the inclosure and to the agitator, said inclosure including an arc-shaped screen.

50 9. A pulping machine, comprising a rotatable shaft carrying paddles, an inclosure therefor including a screen through which the paddles force some material and also including an end plate axially beyond the 55 screen, said end plate being provided with a peripheral opening elsewhere than at the bottom and through which the refuse not forced through the screen is discharged, and a gate controlling the effective size of said 60 peripheral opening.

10. A pulping machine, comprising a rotatable shaft carrying paddles, and an inclosure therefor including a screen through which the paddles force some material and 65 also including an end plate axially beyond

the screen, said end plate being provided with a peripheral opening elsewhere than at the bottom and through which the refuse not forced through the screen is discharged.

11. A pulping machine, comprising a rotating shaft carrying paddles, an inclosure therefor including a screen through which the paddles force some material, said inclosure having at a point axially beyond the 70 end of the screen and elsewhere than at the bottom and a peripheral opening for the discharge of refuse which is not forced through said screen, and a gate controlling the effective size of said peripheral opening.

12. A pulping machine, comprising a rotating shaft carrying paddles, and an inclosure therefor including a screen through which the paddles force some material, said inclosure having at a point axially beyond the 75 end of the screen and elsewhere than at the bottom and a peripheral opening for the discharge of refuse which is not forced through said screen.

13. A pulping machine, comprising a rotatable agitating element including a substantially horizontal shaft carrying paddles, and an inclosure in which said agitator rotates, said inclosure comprising two parts which are both movable relatively to the 80 shaft axis so that when in one position they inclose the agitator and when in another position the inclosure is open and both parts are separated farther than normal from the 85 agitator to give access to the interior of the inclosure and to the agitator, each of said 90 parts of said inclosure including an arc-shaped screen.

14. A pulping machine, comprising a rotatable agitating element including a substantially horizontal shaft carrying paddles, 105 and an inclosure in which said agitator rotates, said inclosure comprising two hinge-mounted parts which are relatively movable so that when in one position they inclose the agitator and when in another position the 110 inclosure is open to give access to the interior and to the agitator, said inclosure including an arc-shaped screen, and bearings for supporting said shaft, said bearings being supported independently of the two 115 hinge-connected parts of the inclosure.

15. A pulping machine, comprising a rotatable agitating element including a substantially horizontal shaft carrying paddles, and an inclosure in which said agitator rotates, said inclosure comprising two hinge-mounted parts pivoted below said shaft so that the two parts may be swung together to inclose the agitator between them or may be separated to give access to their inside 120 surfaces and to the agitator, each of said hinge-mounted parts including an arc-shaped screen through which material may be forced by said agitator.

16. A pulping machine, comprising a ro- 130

- 5 tatable agitating element including a sub-
stantially horizontal shaft carrying paddles,
and an inclosure in which said agitator ro-
tates, said inclosure comprising two hinge-
6 mounted screens pivoted below said shaft
so that the two screens may be swung to-
gether to inclose the agitator between them
or may be separated to give access to their
inside surfaces and to the agitator.
- 10 17. A pulping machine, comprising a ro-
tatable agitating element rotatable on a sub-
stantially horizontal axis, and an inclosure
in which said agitator rotates, said inclosure
comprising a plurality of parts which meet
15 on lines separated from the horizontal plane
through the axis of the rotatable agitator,
said plurality of parts being relatively mov-
able so as to give access to the inside of said
inclosure and including an arc-shaped screen
20 through which material may be forced by
the agitator.
18. A pulping machine, comprising a ro-
tatable agitating element rotatable on a sub-
stantially horizontal axis, and an inclosure
25 in which said agitator rotates, said inclosure
comprising a plurality of parts which meet

on lines separated from the horizontal plane
through the axis of the rotatable agitator,
said plurality of parts being relatively mov-
able so as to give access to the inside of 30
said inclosure, each of said inclosure parts
including an arc-shaped screen through
which material may be forced by said agi-
tator.

19. A pulping machine, comprising a sub-
stantially horizontal shaft carrying paddles,
a laterally openable closure in which said
shaft and paddles rotate, said inclosure in-
cluding a screen which extends completely
40 around the shaft and paddles, and a drain
pan below said inclosure, the upper edge
of said drain pan being lower than the lower
part of said screen so that interference with
the lateral opening of the inclosure is
45 avoided and access to the lower exterior of
the inclosure when it is closed is afforded.

In witness whereof, I have hereunto set
my hand at 5736 East New York St., In-
dianapolis, Indiana, this 26th day of Decem-
ber, A. D. one thousand nine hundred and 50
eighteen.

HARRY W. LOWE.
